MINING APPARATUS

Charles F. Osgood, Claremont, N. H., assignor to
 Sullivan Machinery Company, a corporation of
 Massachusetts

Application February 12, 1932, Serial No. 592,559

50 Claims. (Cl. 262—28)

This invention relates to mining apparatus and more particularly to improvements in the cutting mechanism of an apparatus for mining coal. An object of this invention is to provide an improved coal mining apparatus. Another object is to provide an improved adjustable kerf cutting mechanism for such an apparatus. A further object is to provide an improved kerf cutting mechanism having improved adjustable supporting means for the kerf cutter whereby the latter may be positioned to cut kerfs in horizontal or vertical planes. Yet another object is to provide an improved adjustable kerf cutting mechanism whereby vertical kerfs may be cut in the coal face at any desired location between the ribs and in parallel horizontal planes. Still another object is to provide an improved adjustable kerf cutter supporting structure mounted for universal tilting movement whereby the kerf cutter may be tilted to change its angle in altitude, thereby to accommodate itself to a rolling or pitching coal seam. Still another object of this invention is to provide an improved coal mining apparatus having an improved general arrangement and combination of parts. These and other objects and advantages will, however, hereinafter more fully appear.

In the accompanying drawings there is shown for purposes of illustration one form which the invention may assume in practice.

In these drawings:

Fig. 1 is a plan view of the illustrative embodiment of the improved mining apparatus;

Fig. 2 is a side elevational view of the apparatus shown in Fig. 1;

Fig. 3 is an enlarged horizontal sectional view taken substantially on line 3—3 of Fig. 2, certain parts being shown in plan and others broken away to facilitate illustration;

Fig. 4 is a central longitudinally extending vertical sectional view taken substantially on line 4—4 of Figs. 1 and 3;

Fig. 5 is a detail sectional view taken substantially on line 5—5 of Fig. 3;

Fig. 6 is a central longitudinally extending vertical sectional view taken substantially on line 6—6 of Figs. 1 and 7;

Fig. 7 is a horizontal sectional view taken substantially on line 7—7 of Figs. 2 and 6;

Fig. 8 is a detail vertical sectional view taken substantially on line 8—8 of Fig. 3;

Fig. 9 is a transverse vertical sectional view taken substantially on line 9—9 of Figs. 2 and 6;

Fig. 10 is a transverse vertical sectional view taken substantially on line 10—10 of Fig. 1; and

Fig. 11 is a horizontal sectional view illustrating details of the mechanism shown in Fig. 10.

In this illustrative embodiment of the invention the improved coal mining apparatus is of the combined horizontal and shear cutter, track supported and guided type and generally comprises a portable base, herein a wheeled truck 1, having adjustably mounted thereon a turntable 2, the latter in turn having adjustably mounted thereon through an improved adjustable "parallel motion" supporting structure 3 a rotatable cutter head 4 carrying a pivoted kerf cutter 5. The truck 1 comprises a truck frame 6 mounted on wheels 7 adapted to run along a mine trackway 8. Arranged on the truck frame at the rear of the turntable is the mechanism generally designated 9 for adjusting the turntable and for driving the truck wheels to propel the apparatus along the mine trackway. A motor 10 drives the mechanism 9, while a motor 11 carried by and adjustable with the turntable 2 effects drive of the mechanisms for rotating the turntable, adjusting the supporting structure 3, rotating the cutter head 4 and for actuating and swinging the kerf cutter 5 as hereinafter described.

In this improved construction the turntable 2 comprises a turntable casting 12 having a depending annular flange 13 fitting the inner periphery of and journaled within an annular or ring-like supporting frame 14, the casting 12 having a radial flange 15 overlying the upper edge of the annular frame as shown in Fig. 4. Pivotally mounted on the turntable on parallel vertically disposed hinge shafts 16, 16 is a pair of supporting arms or links 17, 17 arranged in parallel relation and in turn hinged at their forward ends at 18, 18 to a frame or support 19 on which the cutter head 4 is rotatably supported. The motor 11, above referred to, is suspended beneath the turntable, and the power shaft 20 of this motor has fixed thereto a bevel pinion 21 meshing with a bevel gear 22 keyed to the lower end of a vertical shaft 23 suitably journaled within the turntable casting as shown in Fig. 4. Keyed to the upper end of this shaft is a bevel gear 24 meshing with a bevel gear 25 keyed to the rearward end of a horizontal shaft 26 likewise suitably journaled within the turntable casting. This horizontal shaft effects drive of the mechanisms for adjusting the parallel supporting arms, rotating the cutter head and for swinging and actuating the kerf cutter as will later be described.

The mechanism for rotating the turntable 4 relative to the annular supporting frame 14 comprises a spur gear 27 keyed to the vertical shaft 55

23, and, as shown in Fig. 3, meshing with spur gears 28 and 29 arranged on parallel axes at opposite sides of the shaft 23. Rotatable with and driven by the spur gear 28 is a worm 30 meshing 5 with a slow speed worm wheel 31. This worm wheel is connectible by a usual multiple disc clutch 32 having any suitable type of operating means to a transverse shaft 33 likewise suitably journaled within the turntable casting. Fixed 10 to this shaft is a worm 34 meshing with a worm wheel 35 suitably journaled within the turntable casting and keyed to a vertical shaft 36. This vertical shaft is connectible by a sliding clutch 37 to a spur gear 38 supported by the shaft and 15 meshing with the teeth of a circular rack 39 formed on the inner periphery of the annular supporting frame 14; the gear 38, when released from the shaft 36, being freely rotatable on the shaft. Rotatable with and driven by the spur 20 gear 29 is a worm 40 meshing with a fast speed worm wheel 41 having its teeth oppositely inclined from the teeth of the worm wheel 31 and operative, upon application of a multiple disc clutch 42, to effect drive of the shaft 33 at a fast 25 speed in a direction opposite from the slow speed drive described above. It will thus be seen that when the clutch 37 is connected and one or the other of the disc clutches 32, 42 is applied, the turntable 2 may be rotated relative to the annular supporting frame 14 to swing the cutting mechanism about the turntable axis at either a 30 relatively high cutter positioning speed in one direction or at a relatively low cutting speed in the opposite direction.

35 If desired, the teeth of the worm gears 34, 35 may be self-locking to thereby lock automatically the turntable against rotation when the disc clutches 32, 42 are released. However, if desired, there may be provided a separate turntable lock 40 comprising in the outer edge of the turntable casting a series of notches 43 with which cooperate a sliding locking bolt 44 mounted in the guide-way formed on a bracket 45 secured to the annular supporting frame. The locking bolt, when 45 in its inner position, projects within one of the notches 43 to lock the turntable 2 against rotation relative to the annular supporting frame. The turntable release clutch 37 comprises, as shown in Figs. 3 and 4, clutch plungers 46 guided 50 within slots 47 formed in the shaft 36. Rotatably mounted within the shaft 36 is a clutch operating shaft 48 having an operating handle 49, and formed on its lower end a pair of grooves 50. When the element 48 is in the position shown in 55 Fig. 4, the clutch plungers are projected within notches 51 formed in the gear 38, thereby locking the gear to the shaft 36. When the element 48 is turned to bring the grooves 50 in registry with the slots 47, the clutch plungers are free to 60 slide inwardly, thereby to release the gear 38 from the shaft 36. The clutch 37, when released, cuts loose, so to speak, the turntable from its rotating mechanism, thereby permitting the turntable to rotate freely relative to the annular supporting frame 14 for a purpose to be later described.

65 The parallel arms 17, 17 form a "parallel motion" supporting structure for the cutter head 4 so that, when the arms are swung relative to the turntable, the cutter head is moved horizontally, 70 while the head axis is always maintained parallel to a longitudinally extending vertical plane. The mechanism for swinging this arm structure comprises a worm 53 keyed to the horizontal shaft 26 and meshing with a worm wheel 54 connectible by 75 a suitable multiple disc clutch 55 (see Fig. 8) to

a transverse shaft 56 suitably journaled within the turntable casting. Keyed to the opposite ends of the shaft 56 are worms 57, 57 meshing with worm gear racks 58, 58 formed on the rear ends of the arms 17, 17 respectively as shown in Fig. 3. It will thus be seen that, when the friction clutch 55 is applied, the parallel arms may be swung about their pivots relative to the turntable 2 through the connections 21, 22, 24, 25, 53, 54 and 57 driven by the motor 11. The motor 11 is of the 10 reversible type and the arms may therefore be swung in either of opposite directions depending upon the direction of the motor rotation.

The mechanism for actuating the kerf cutter 5 will now be described. Keyed to the forward 15 end of the shaft 26, as shown in Fig. 4, is a bevel gear 62 meshing with a bevel gear 63 journaled within the turntable casting upon a vertical axis lying midway between and in the same transverse vertical plane as the axes of the hinge shafts 16, 16. The gear 63 meshes with a bevel gear 64 keyed to a longitudinally extending shaft 65 arranged midway between and parallel with the arms 17, 17, and the rearward end of this shaft is journaled within a swiveled bearing block 66 20 arranged with its axis coincident with the axis of the bevel gear 63. The forward end of the shaft 65 is journaled within a swiveled bearing block 67 journaled on a vertical shaft 68 carried by the cutter head supporting frame 19, and keyed to the 25 forward end of the shaft 65 is a bevel gear 69 meshing with a bevel gear 70 journaled within the frame 19 about a vertical axis coincident with the axis of the swiveled block 67. The bevel gear 70 meshes with a bevel gear 71 keyed to the rearward end of a horizontal shaft 72 and this shaft is journaled at its rearward end within the head supporting frame 19 and at its forward end within the frame 73 of the cutter head 4. This shaft 72 is arranged with its axis coincident with the 30 cutter head axis and has keyed thereto, at its forward end, a bevel gear 74 meshing with a bevel gear 75 connectible by a sliding clutch 76 to a vertical shaft 77. Keyed to the outer end of the shaft 77 is a chain sprocket 78 which engages and drives the endless cutter chain 79 of the kerf cutter. It will thus be seen that the cutter chain 79 may be driven, due to the arrangement of the shafts 26, 65, 72 and the swiveled 35 bearing blocks for the shaft 65, irrespective of the position of the cutter head and the adjustable supporting arms relative to the turntable. The cutter chain 79 may be disconnected from its drive at will simply by releasing the clutch 76.

Now referring to the mechanism for effecting 40 swinging of the kerf cutter 5 about its pivotal axis (i. e. the axis of the shaft 77) relative to the cutter head 4, it will be noted that rotatable with and driven by the bevel gear 75 is a shaft 80 which in turn has fixed thereto and drives a bevel gear 81 constantly meshing with reversely rotatable bevel gears 82 and 83. These gears 82 and 83 are loosely journaled on a transverse shaft 84 in turn suitably journaled within the cutter head frame 73. The reverse bevels 82, 83 are selectively connectible to the shaft 84 by means of multiple disc clutches 85 and 86 respectively of a usual design operated by a suitable shifter mechanism 87 controlled by a handle 88. Connectible to the shaft 84 is a worm 89 meshing with a worm wheel 90 fixed to a shaft 91, herein arranged parallel with the shaft 77 and likewise journaled in the cutter head frame. Also fixed to the shaft 91, as shown in Fig. 9, is a spur pinion 92 meshing 45 with the teeth of an internal gear 93, herein 50 55 60 65 70 75 80 85 90 95 100

formed integral with a cylindrical frame 94 to which the kerf cutter hanger 95 is secured. The frame 94 is mounted within the cutter head frame for rotation about an axis coincident with the axis of the cutter chain driving shaft 77, and is rotatably mounted within a bore 96 formed in the cutter head frame. A thrust ring 97 attached to the cutter head frame retains the cylindrical frame 94 in its bore. The worm 89 is connectible to the shaft 84 by a sliding clutch element 98 and cooperating clutch elements 99, 100 carried by the worm and shaft respectively. The sliding clutch element 98 is provided with usual shipper mechanism 101 operated by a handle 102. It will thus be seen that depending upon which friction clutch 85, 86 is applied, the kerf cutter may be swung about its pivot relative to the cutter head at a speed appropriate for cutting and in either of opposite directions. If desired, the kerf cutter hanger 95 may be of the extension type as indicated in broken lines in Fig. 2 so that the kerf cutter 5 may be positioned to cut a horizontal kerf at or near the level of the mine floor or, if desired, the cutter head may be provided with an offset pivot and telescopic adjustment of the type disclosed in my copending application, Serial No. 432,541, filed Mar. 1, 1930, to increase the range of adjustment of the kerf cutter.

The mechanism for rotating the cutter head 4 about its axis relative to the cutter head support 19 herein comprises a worm 103 connectible to the shaft 84 and meshing with a worm wheel 104 fixed to a longitudinally extending shaft 105, herein arranged parallel with the shaft 72. This shaft is suitably journaled within a cutter head frame and carries a pinion 106 (see Fig. 7) meshing with the teeth of an internal gear 107, herein formed integral with a cylindrical bearing sleeve 108 secured to the cutter head support 19 and on which the cutter head is rotatably mounted. The worm 103 is connectible to the shaft 84 by a sliding clutch element 111 cooperating with clutch elements 112 and 113 carried by the worm and shaft respectively. This sliding clutch element is provided with usual shipper mechanism 114 operated by a handle 115. It will therefore be evident that the cutter head 4 may be rotated about its axis in either of opposite directions under the control of friction clutches 85, 86. The worm gearings 89, 90 of the kerf cutter swinging mechanism and 103, 104 of the head rotating mechanism are self-locking and, upon release of the clutches, maintain automatically the kerf cutter and cutter head in their positions of adjustment.

The turntable adjusting mechanism will now be described. As mentioned above, the turntable 2 is mounted on the truck for vertical and universal tilting adjustments relative thereto and, in this instance, the annular frame 14 supporting the turntable has attached thereto a plurality of depending brackets 120, the lower ends of which are shaped to engage respectively with up-standing guide members 121, herein in the form of screw pedestals which are secured to the truck frame. These screw pedestals serve as guides to prevent any substantial lateral movement of the turntable supporting frame and attached parts relative to the truck frame during adjustment of the turntable. Secured to these depending brackets 120 are screw nuts 122 (see Fig. 5) which are threadedly engaged with vertical screws 123 supported at their upper ends by the upstanding guide members 121 and at their lower ends in step bearings 124 formed in bearing

brackets 125 attached to the bottom of the truck frame. It will be noted that the nuts 122 are so connected to the feet of the depending brackets as to permit a slight relatively rocking movement between the parts. The three sets of screws and guiding members constitute upright supports for the annular supporting frame 14, and the latter can be adjusted vertically in parallelism or angularly to change its angle in altitude by suitable rotation of the screws. The mechanism for separately or simultaneously rotating the screws will be later described.

Now referring to the mechanism for driving the truck wheels, it will be noted that the motor 10, which is preferably of the reversible electrical type, has its power shaft connected to a worm 132 meshing with a worm wheel 133 rotatably mounted on a transverse shaft 134 suitably journaled within a frame 135 suitably secured to the truck frame. This worm wheel is operatively connectible to the shaft 134 by means of a multiple disc clutch 136 of a usual design having a suitable operating mechanism including a hand lever 137. Fixed to this transverse shaft is a brake drum 138 which is engaged by a brake band 139 also arranged to be controlled by the hand lever 137. When this hand lever is swung in one direction, the clutch 136 is applied and the brake 139 released, and in the opposite direction, the brake is applied and the clutch released. Journaled on the shaft 134 is a spur gear 140 connectible with the shaft by a jaw clutch member 141 splined to the shaft, and this gear meshes with a spur gear 142. This spur gear 142 is connected to a transverse shaft 143 suitably journaled within the frame 135. Keyed to the shaft 134 is a spur pinion 144 meshing with a spur gear 145 (see Fig. 11) secured to a transverse shaft 146 arranged parallel with the shaft 134. Splined to the shaft 146 is a slideable pinion 147 adapted to mesh with a spur gear 148 keyed to a sleeve 149, herein formed integral with the gear 140. If desired, suitable operating mechanism may be provided for the clutch 141 and the sliding pinion 147 so that, when one is connected, the other is released. As illustrated, secured to the shaft 143 is a chain sprocket 150 connected by an endless chain connection 151 to a chain sprocket secured to the rear truck axle. The front and rear truck axles are connected together by a usual chain and sprocket connection 152 as shown in Fig. 4. From the foregoing description it will be evident that when the jaw clutch 141 is shifted to connect the spur gear 140 to the shaft 134 and the pinion 147 is out of mesh with the gear 148, the truck wheels may be driven at a relatively high speed from the motor 10 through the worm gearing 132, 133, friction clutch 136, shaft 134, spur gearing 140, 142 and the chain and sprocket connection 150, 151 and 152. It will also be evident that when the jaw clutch 141 is in its released position and the spur pinion 147 is slid into meshing engagement with the gear 148, the truck wheels may be driven at a relatively slow speed appropriate for cutting through the reduction gearing 144, 145, 147 and 148. Upon reversal of the motor 10, the truck wheels may be driven to propel the apparatus in a reverse direction at either a relatively high or a relatively low speed.

The mechanism for driving the turntable elevating and tilting screws 123 from the motor 10 herein comprises a bevel pinion 153 (see Fig. 10) journaled on the shaft 134 and connectible to the shaft by a jaw clutch 141. This bevel pinion meshes with a bevel gear 154 fixed to a vertical

shaft 155 suitably journaled within the frame 135. Keyed to the shaft 155 is a chain sprocket 156 which engages and drives an endless transmission chain 157. Idler sprockets 158 and 159 serve to guide the chain 157 relative to chain sprockets 160 rotatably mounted upon each of the screws 123 at its lower end, as shown in Fig. 5, and these sprockets are driven by the endless chain 157. As shown, these chain sprockets 160 have formed thereon clutch teeth 161 adapted to engage with similar teeth of clutch members 162 and each provided with a groove 163 in engagement with an arm 164 attached to vertical operating shafts 165. The shafts 165 extend through the top plate of the truck and are each provided with a conveniently located handle 166 by which the movement of the clutch members 162 may be controlled. It will thus be seen that, when all the clutches 162 are in a position to connect the chain sprockets 160 to the screws 123, the latter may be simultaneously rotated to move the turntable, together with the cutting mechanism supported thereby into different elevated positions relative to the truck. It will also be noted that by releasing certain of these clutches and connecting certain others, the screws may be rotated to effect universal tilting movement of the turntable relative to the truck to change the angle in altitude of the cutting mechanism.

The mode of operation of the improved mining apparatus will now be described. The apparatus is propelled along the mine trackway at a relatively high transport speed through the truck wheel driving gearing 132, 133, 140, 142 driven by the motor 10. When the working face is reached, the high truck wheel drive is disconnected from the motor by releasing the friction clutch 136 and the sliding clutch 141. If it is desired to cut a horizontal kerf in the coal face in accordance with the well known arcweld method, the operator applies the friction clutch 42 of the fast speed turntable swinging mechanism, thereby causing the turntable 2, together with the cutting mechanism supported thereby, to be swung horizontally about the turntable axis at a cutter positioning speed from the central position shown in Fig. 1 to a position wherein the tip end of the kerf cutter is disposed adjacent the right hand rib of the entry. When the parts are thus disposed, the operator releases the friction clutch 42 of the turntable swinging mechanism and the turntable is then locked in position against movement relative to the truck. The jaw clutch 76 is then connected, thereby connecting the cutter chain in driving relation with the motor 11. The pinion 147 of the slow speed truck driving mechanism is then slid into meshing engagement with the gear 148, and, upon application of the friction clutch 136, the truck wheels are driven to propel the apparatus bodily in a forward direction along the mine trackway at a relatively slow cutting speed, thereby summing the kerf cutter 5 within the coal. The friction clutch 136 is then released and the brake 138 set. The operator then applies the friction clutch 32 of the slow speed turntable swinging mechanism, and the turntable 2, together with the cutting mechanism supported thereby, is swung horizontally about the turntable axis at a slow cutting speed to effect horizontal swinging movement of the kerf cutter in its plane transversely across the coal face to make a horizontal cut therein. After the tip end of the kerf cutter has reached the left hand rib and the swinging cut in the coal has been completed, the clutches 32 and the

brake 138 are released, and, upon application of the friction clutch 136 of the truck wheel drive and the reversal of the motor 10, the apparatus is propelled bodily rearwardly along the mine trackway at a slow cutting speed to withdraw the kerf cutter from the coal. The kerf cutter 5 may be adjusted to cut kerfs in different horizontal planes by adjusting the elevation of the turntable 2 relative to the truck and by rotating the cutter head to position the kerf cutter above the head axis.

It will be noted that during the horizontal cutting operation described above, for instance, when it is desired to cut on a rolling or pitching coal seam, the cutting mechanism may be universally tilted to change its angle in altitude simply by disconnecting certain of the elevating screws 123 from the motor 10 while others are rotated, thereby causing the turntable 2 to be tilted relative to the horizontal. For instance, if it is desired to tilt the tip end of the kerf cutter downwardly, this may be accomplished by disconnecting the clutches for the front elevating screws, while the rear elevating screw is connected to the motor 10, thereby causing the rear edge of the turntable to be elevated. Conversely, if it is desired to tilt the tip end of the kerf cutter upwardly, the rear elevating screw may be disconnected from the motor while the front elevating screws are rotated, thereby causing the forward edge of the turntable to be tilted upwardly.

A shear or vertical cut may be inserted in the coal face simply by applying one or the other of the reverse frictions 85, 86 of the head rotating mechanism, thereby rotating the cutter head about its axis to bring the kerf cutter 5 to a position to swing vertically. During the shearing operation the kerf cutter is first sumped in, then swung downwardly from its plane and thereafter withdrawn from the coal in a manner similar to that described above in connection with horizontal cutting in accordance with the arcweld method. If it is desired to cut vertical kerfs in different parallel planes between the ribs of the entry, this may be accomplished by applying the friction clutch 55 of the swinging mechanism for the arms 17, 17 of the "parallel motion" structure to move the cutter head horizontally relative to the turntable, the arm structure maintaining the kerf cutter at all times parallel to a longitudinal vertical plane during such swinging movement. It will further be noted that by rotating the cutter head the kerf cutter may be moved through an arc of a circle to shearing positions at either side of the head axis.

When it is desired to insert a vertical or shearing cut in the mine wall when the apparatus is supported and guided by a curved trackway, the apparatus is operated in the following manner: With the kerf cutter 5 in shearing position, the turntable 2 is rotated to position the cutting mechanism laterally until the tip end of the kerf cutter engages the rib of the entry. The turntable is then locked against rotation and the kerf cutter is swung upwardly to a position adjacent the mine roof. When the parts are thus disposed, the apparatus is propelled along the mine trackway at a slow speed to cause the tip end of the kerf cutter to penetrate the coal. The turntable lock is then released and the turntable is permitted to rotate freely relative to the truck as the apparatus is propelled bodily along the mine trackway, and as a result, as the apparatus moves along the curved trackway, the kerf is sumped 75

within the coal in the manner well known to those skilled in the art, the free rotation of the turntable relative to the truck, as the latter moves along the trackway, preventing binding or cramping of the kerf cutter in the kerf. The kerf cutter is then swung about its pivot downwardly in its plane and thereafter withdrawn from the coal to complete the shearing cut.

As a result of this invention, it will be noted that an improved coal mining apparatus is provided having an improved adjustable kerf cutting mechanism whereby vertical kerfs may be cut at any desired location between the ribs, and horizontal kerfs may be cut in the coal face at different elevations. It will also be evident that by the provision of the tilting turntable mounting for the kerf cutting mechanism, the kerf cutter may be universally tilted to change its angle in altitude, thereby to accommodate itself to rolling or pitching coal seams. It will still further be noted that an improved coal mining apparatus is provided wherein the adjusting mechanism for the kerf cutting mechanism is extremely flexible, it being possible to adjust the kerf cutting mechanism relative to the turntable or with the turntable relative to the truck, thereby to position the kerf cutter into different parallel vertical planes. These and other uses and advantages of the improved mining apparatus will be clearly apparent to those skilled in the art.

While there is in this application specifically described one form which this invention may assume in practice, it will be understood that this form of the same is shown for purposes of illustration and that the invention may be modified and embodied in various other forms without departing from its spirit or the scope of the appended claims.

40 What I claim as new and desire to secure by Letters Patent is:

1. In a mining apparatus, a portable base, a horizontal turntable on said base, a rotatable cutter head carrying a kerf cutter and rotatable on its axis to effect bodily adjustment of the kerf cutter into different cutting planes and an adjustable supporting structure intervening said turntable and said cutter head for supporting the latter and for swinging the cutter head horizontally relative to the turntable while the latter remains stationary and while the head axis is always maintained parallel to a common straight line.

2. In a mining apparatus, a portable base, a rotatable cutter head carrying a kerf cutter and rotatable on its axis to effect bodily adjustment of the kerf cutter into different cutting planes, a parallel motion supporting structure between said base and cutter head for adjusting the latter horizontally relative to said base, and motor operated devices for adjusting said supporting structure and for rotating said cutter head relative to said supporting structure.

3. In a mining apparatus, a portable base, a rotatable cutter head carrying a pivoted kerf cutter and rotatable on its axis to effect bodily adjustment of the kerf cutter into different cutting planes, a parallel motion supporting structure between said base and cutter head for adjusting the latter horizontally relative to said base, and motor operated devices for adjusting said supporting structure, for rotating said cutter head relative to said supporting structure and for swinging said kerf cutter relative to said cutter head.

4. In a mining apparatus, a portable base, a rotatable cutter head carrying a kerf cutter and rotatable on its axis to effect bodily adjustment of the kerf cutter into different cutting planes, a parallel motion supporting structure between said base and cutter head for adjusting the latter horizontally relative to said base while the head axis is always maintained parallel to a common straight line, and motor operated devices for adjusting said supporting structure relative to said base and for rotating said cutter head relative to said supporting structure.

5. In a mining apparatus, a portable base, a swingable arm structure overhanging said base and swingable horizontally relative thereto, a cutter head rotatably mounted on the outer extremity of said arm structure and carrying a kerf cutter and rotatable on its axis to effect bodily adjustment of the kerf cutter into different cutting planes, motor operated devices for swinging said arm structure and for rotating said cutter head, and mechanism for maintaining automatically the axis of said cutter head parallel to a common straight line during swinging of said arm structure horizontally.

6. In a mining apparatus, a portable base, a swingable arm structure overhanging said base and swingable horizontally relative thereto, a cutter head rotatably mounted on the outer extremity of said arm structure and carrying a pivoted kerf cutter and rotatable on its axis to effect bodily adjustment of the kerf cutter into different cutting planes, motor operated devices for swinging said arm structure, for rotating said cutter head and for swinging said kerf cutter relative to said cutter head, and mechanism for maintaining automatically the axis of said cutter head parallel to a common straight line during swinging of said arm structure horizontally.

7. In a mining apparatus, a portable base, a swingable arm structure overhanging said base and swingable horizontally relative thereto, a cutter head rotatably mounted on the outer extremity of said arm structure and carrying a kerf cutter and rotatable on its axis to effect bodily adjustment of the kerf cutter into different cutting planes, and motor operated devices for swinging said arm structure and for rotating said cutter head, said arm structure being swingable relative to said base to move the cutter head into different horizontal positions relative to said base while the head axis is always automatically maintained parallel to a common straight line.

8. In a mining apparatus, a portable base carrying a turntable, a horizontal parallel motion supporting structure mounted in superimposed relation on and overlying said base and turntable and at its forward extremity overhanging said base, said supporting structure swingable horizontally relative to said base, and a kerf cutter carried on the outer overhanging extremity of said supporting structure, said supporting structure being swingable horizontally relative to said base to move said kerf cutter into different horizontal positions relative to said base while said kerf cutter is always maintained parallel to a common straight line.

9. In a mining apparatus, a portable base, a horizontal turntable mounted on said base, a parallel motion arm structure mounted on and overlying said turntable and overhanging said base, and a kerf cutter mounted on the outer extremity of said arm structure, said arm structure being adjustable horizontally relative to said

turntable to move the kerf cutter into different horizontal positions relative to said base.

10. In a mining apparatus, a portable base, a horizontal turntable mounted on said base, a parallel motion arm structure mounted on and overlying said turntable and overhanging said base, and a rotatable cutter head mounted on the outer extremity of said arm structure and carrying a kerf cutter, said arm structure being swingable horizontally relative to said turntable to move the cutter head into different horizontal positions relative to said base.

11. In a mining apparatus, a portable base, a parallel motion arm structure mounted on said base and extending forwardly in advance of the latter, a rotatable cutter head mounted on the outer extremity of said arm structure for rotation relative thereto and carrying a kerf cutter bodily adjustable about the head axis, and a motor mounted on said base and relative to which said arm structure is adjustable for adjusting said arm structure horizontally relative to said base and motor while the latter remains stationary and for rotating said cutter head.

12. In a mining apparatus, a portable base, a parallel motion arm structure mounted on said base and extending forwardly in advance of the latter, a rotatable cutter head mounted on the outer extremity of said arm structure for rotation relative thereto and carrying a pivoted kerf cutter bodily adjustable about the head axis, and a motor mounted on said base and relative to which said arm structure is adjustable for adjusting said arm structure horizontally relative to said base and motor while the latter remains stationary, for rotating said cutter head and for swinging said kerf cutter relative to said cutter head.

13. In a mining apparatus, a portable base, a horizontal turntable mounted on said base, a parallel motion arm structure mounted on and overlying said turntable and extending forwardly in advance of said base, a rotatable cutter head mounted on the outer extremity of said arm structure and carrying a kerf cutter, and a motor mounted on said turntable for rotating the latter and for swinging said arm structure relative to said turntable.

14. In a mining apparatus, a portable base, a horizontal turntable mounted on said base, a parallel motion arm structure mounted on and overlying said turntable and extending forwardly in advance of said base, a rotatable cutter head mounted on the outer extremity of said arm structure and carrying a kerf cutter, and a motor mounted on said turntable for rotating the latter, for swinging said arm structure relative to said turntable and for rotating said cutter head.

15. In a mining apparatus, a portable base, a horizontal turntable mounted on said base, a parallel motion arm structure mounted on and overlying said turntable and extending forwardly in advance of said base, a rotatable cutter head mounted on the outer extremity of said arm structure and carrying a kerf cutter, and a motor mounted on said turntable for rotating the latter, for swinging said arm structure relative to said turntable, for rotating said cutter head, and for swinging said kerf cutter relative to said cutter head.

16. In a mining apparatus, a portable base, a supporting structure mounted on said base and swingable horizontally relative thereto, a cutter head mounted on the outer extremity of said supporting structure and carrying a kerf cutter

bodily adjustable about the head axis, and motor operated devices for swinging said supporting structure and for rotating said cutter head relative to said supporting structure, said supporting structure maintaining automatically the cutter head axis parallel to a common straight line during swinging of said supporting structure relative to said base.

17. In a mining apparatus, a portable base, a horizontal turntable mounted on said base, a supporting structure mounted on and overlying said turntable, a rotatable cutter head mounted on said supporting structure and carrying a kerf cutter, means for rotating said turntable to swing said supporting structure therewith to move the cutter head horizontally about the turntable axis relative to said base, and means for swinging said supporting structure relative to said turntable, said supporting structure maintaining automatically the cutter head axis parallel to a common straight line during swinging of said supporting structure relative to said turntable.

18. In a mining apparatus, a portable base, a turntable mounted for rotation on said base and for adjustment vertically relative thereto, a parallel arm structure mounted on and overlying said turntable, said arm structure swingable relative to said turntable, and a rotatable cutter head mounted on the outer overhanging extremity of said arm structure and carrying a kerf cutter.

19. In a mining apparatus, a portable base, a rotatable turntable mounted on said base for universal tilting movement relative thereto, a parallel arm structure mounted on and overlying said turntable, said arm structure swingable horizontally relative to said turntable, and a rotatable cutter head mounted on the outer overhanging extremity of said arm structure and carrying a kerf cutter.

20. In a mining apparatus, a portable base, a rotatable turntable mounted on said base for adjustment vertically and for universal tilting movement relative thereto, a parallel arm structure mounted on and overlying said turntable, said arm structure swingable horizontally relative to said turntable, and a rotatable cutter head mounted on the outer overhanging extremity of said arm structure and carrying a kerf cutter.

21. In a mining apparatus, a portable base, a turntable mounted on said base for adjustment vertically relative thereto, an adjustable arm structure mounted on and overlying said turntable, said arm structure swingable horizontally relative to said turntable, a rotatable cutter head mounted on the outer extremity of said arm structure and carrying a kerf cutter, and means for maintaining automatically the cutter head axis parallel to a common straight line during swinging adjustment of said arm structure horizontally relative to said turntable.

22. In a mining apparatus, a portable base, a turntable mounted on said base for universal tilting movement relative thereto, an adjustable arm structure mounted on and overlying said turntable, a rotatable cutter head mounted on the outer extremity of said arm structure and carrying a kerf cutter, and means for maintaining automatically the cutter head axis parallel to a common straight line during adjustment of said arm structure relative to said turntable.

23. In a mining apparatus, a portable base, a turntable mounted on said base for adjustment vertically and for universal tilting movement relative thereto, an adjustable arm structure mounted on and overlying said turntable, a ro-

- tatable cutter head mounted on the outer extremity of said arm structure and carrying a kerf cutter, and means for maintaining automatically the cutter head axis parallel to a common straight line during adjustment of said arm structure relative to said turntable.
24. In a mining apparatus, a portable base, a horizontal turntable mounted on said base for rotation relative thereto about a normally vertical axis; an arm-like frame structure mounted on and overlying said turntable and at its forward extremity overhanging said base, said frame structure swingable horizontally relative to said base and swingable with or relative to said turntable; a support pivotally mounted on the outer overhanging extremity of said frame structure to swing relative thereto about an axis parallel with said frame structure axis, a kerf cutter pivotally mounted on said support, and motor operated devices for simultaneously swinging said frame structure and support about their respective axes thereby to maintain said kerf cutter parallel to a common straight line during swinging of said frame structure relative to said turntable from one side of said base to the other.
25. In a mining apparatus, a portable base, a horizontal turntable mounted on said base for rotation about a normally vertical axis, an arm-like frame structure mounted on and overlying said turntable and at its forward extremity overhanging said base, said frame structure swingable horizontally relative to said base and swingable with or relative to said turntable; a support pivotally mounted on the outer overhanging extremity of said frame structure to swing relative thereto about an axis parallel with said frame structure axis, a cutter head rotatably mounted on said support, a kerf cutter pivotally mounted on said cutter head and rotatable with said head into different positions about the head axis, and motor operated devices for simultaneously swinging said frame structure and support about their respective axes thereby to maintain the cutter head axis parallel to a common straight line during swinging of said frame structure relative to said turntable from one side of said base to the other.
26. In a mining apparatus, a portable base, a turntable mounted on said base for adjustment in a vertical direction relative thereto, an adjustable supporting structure mounted on and overlying said turntable, said supporting structure including a frame swingable horizontally relative to said turntable, a rotatable cutter head mounted on the outer extremity of said supporting structure and carrying a kerf cutter and rotatable on its axis to effect bodily adjustment of the kerf cutter into different cutting planes, and means for maintaining automatically the cutter head axis parallel to a common straight line during swinging adjustment of said frame of said supporting structure horizontally relative to said turntable.
27. In a mining apparatus, a portable base, a turntable mounted on the base for tilting movement relative to the horizontal, an adjustable supporting structure mounted on and overlying said turntable, a rotatable cutter head mounted on the outer extremity of said supporting structure and carrying a kerf cutter, and means for maintaining automatically the cutter head axis parallel to a common straight line extending longitudinally of the base during adjustment of said supporting structure horizontally relative to said turntable.
28. In a mining apparatus, a portable base, a turntable mounted on the base for universal tilting movement relative to the horizontal, an adjustable supporting structure mounted on and overlying said turntable, a rotatable cutter head mounted on the outer extremity of said supporting structure and carrying a kerf cutter, and means for maintaining automatically the cutter head axis parallel to a common straight line extending radially of the turntable during adjustment of said supporting structure horizontally relative to said turntable.
29. In a mining apparatus, a portable base, a turntable mounted on the base for adjustment in a vertical direction and for tilting movement relative to the horizontal, an adjustable supporting structure mounted on and overlying said turntable, a rotatable cutter head mounted on the outer extremity of said supporting structure and carrying a kerf cutter and rotatable on its axis to effect bodily adjustment of the kerf cutter into different cutting planes, and means for maintaining automatically the cutter head axis parallel to a common straight line during adjustment of said supporting structure horizontally relative to said turntable.
30. In a mining apparatus, a portable base, a turntable mounted on the base for adjustment in a vertical direction and for universal tilting movement relative thereto, an adjustable supporting structure mounted on and overlying said turntable, a rotatable cutter head mounted on the outer extremity of said supporting structure and carrying a kerf cutter, and means for maintaining automatically the cutter head axis parallel to a common straight line extending longitudinally of the base during adjustment of said supporting structure horizontally relative to said turntable.
31. In a mining apparatus, a portable base, kerf cutting mechanism on said base including a cutter head rotatable about an axis extending longitudinally of the base and a kerf cutter pivotally mounted on said cutter head for swinging movement relative thereto, and means disposed at the top of and overlying said base and movable across the top of the latter for adjusting said cutter head in a direction horizontally relative to said base while the head axis is always automatically maintained longitudinally of the base and always parallel to a common straight line, said adjusting means including a frame swingable horizontally relative to said base and adjustable angularly relative to the cutter head axis during swinging of said frame.
32. In a mining apparatus, a portable base, kerf cutting mechanism on said base including a cutter head rotatable about an axis extending longitudinally of the base, and a kerf cutter pivotally mounted on said cutter head for swinging movement relative thereto, means for adjusting said cutter head in a vertical direction relative to the base while maintaining the head axis horizontal, and means for swinging said cutter head in a direction horizontally relative to said base while the head axis is always automatically maintained longitudinally of the base and always parallel to a common straight line.
33. In a mining apparatus, a portable base, kerf cutting mechanism on said base including a kerf cutter swingable in a vertical plane extending longitudinally of said base, and means disposed at the top of and overlying said base and movable across the top of the latter for swinging said kerf cutter bodily in a direction

- horizontally relative to said base while said kerf cutter is at all times automatically maintained longitudinally of said base and always parallel to a longitudinally extending vertical plane.
34. In a mining apparatus, a portable base, a horizontal turntable on said base, a rotatable cutter head carrying a kerf cutter and rotatable on its axis to effect bodily adjustment of the kerf cutter into different cutting planes, and an adjustable supporting structure intervening said turntable and said cutter head for supporting the latter and for adjusting the cutter head horizontally relative to the turntable while the latter remains stationary and while the head axis is always automatically maintained parallel to a common straight line, and a motor on said turntable relative to which said cutter head is adjustable for adjusting said cutter head horizontally relative to the turntable.
35. In a mining apparatus, a portable base, a rotatable cutter head carrying a kerf cutter and rotatable on an axis extending longitudinally of the base, a parallel motion supporting structure between said base and cutter head for effecting a parallel motion adjustment of the latter horizontally relative to said base, and motor operated devices for adjusting said supporting structure and for rotating said cutter head relative to said supporting structure and including a motor mounted on said base and relative to which said supporting structure is adjustable.
36. In a mining apparatus, a portable base, a rotatable cutter head carrying a pivoted kerf cutter and rotatable on an axis extending longitudinally of the base, a parallel motion supporting structure between said base and cutter head for adjusting the latter horizontally relative to said base, and motor operated devices for adjusting said supporting structure, for rotating said cutter head relative to said supporting structure and for swinging said kerf cutter relative to said cutter head and including a motor mounted on said base and relative to which said supporting structure is adjustable.
37. In a mining apparatus, a portable base, a rotatable cutter head carrying a kerf cutter and rotatable on an axis extending longitudinally of the base, a parallel motion supporting structure between said base and cutter head for adjusting the latter horizontally relative to said base while the head axis is always maintained parallel to a common straight line, and motor operated devices for adjusting said supporting structure relative to said base and for rotating said cutter head relative to said supporting structure and including a motor mounted on said base and relative to which said supporting structure is adjustable.
38. In a mining apparatus, a portable base, a parallel motion arm structure mounted on and overlying said base, said arm structure at its forward extremity overhanging said base, a cutter head rotatably mounted on the outer extremity of said arm structure, a kerf cutter pivotally mounted on said cutter head, said arm structure being adjustable horizontally relative to the base to move the kerf cutter into different cutting positions relative to the base, and a motor on said base and relative to which said arm structure is adjustable for swinging said arm structure relative to said base and for rotating said cutter head.
39. In a mining apparatus, a portable base, a parallel motion arm structure mounted on and overlying said base, said arm structure at its forward extremity overhanging said base, a cutter head rotatably mounted on the outer extremity of said arm structure, a kerf cutter pivotally mounted on said cutter head, said arm structure being adjustable horizontally relative to the base to move the kerf cutter into different cutting positions relative to the base, and a motor on said base and relative to which said arm structure is adjustable for swinging said arm structure relative to said base, for rotating said cutter head and for swinging said kerf cutter relative to said cutter head.
40. In a mining apparatus, a portable base, a rotatable cutter head carrying a pivoted kerf cutter, a parallel motion supporting structure between said base and cutter head and swingable horizontally about parallel vertical axes for adjusting the cutter head horizontally relative to said base, and motor operated devices for adjusting said supporting structure, for rotating said cutter head relative to said supporting structure independently of movement of the latter and for swinging said kerf cutter relative to said cutter head and including a motor mounted on said base and relative to which said supporting structure is adjustable.
41. In a mining apparatus, a portable base, a rotatable cutter head carrying a pivoted kerf cutter, a parallel motion supporting structure between said base and cutter head and swingable horizontally about parallel vertical axes for adjusting the cutter head horizontally relative to said base, and motor operated devices for adjusting said supporting structure, for rotating said cutter head relative to said supporting structure independently of movement of the latter and for swinging said kerf cutter relative to said cutter head and including a motor mounted on said base and relative to which said supporting structure is adjustable.
42. In a mining apparatus, a portable base, a parallel motion arm structure mounted on and overlying said base, said arm structure at its forward extremity overhanging said base, a cutter head rotatably mounted on the outer extremity of said arm structure, a kerf cutter pivotally mounted on said cutter head, said arm structure including arms adjustable horizontally relative to the base about parallel vertical axes to move the kerf cutter into different cutting positions relative to the base, and a motor on said base and relative to which said arm structure is adjustable for swinging said arm structure relative to said base and for rotating said cutter head.
43. In a mining apparatus, a portable base, a parallel motion arm structure mounted on and overlying said base, said arm structure at its forward extremity overhanging said base, a cutter head rotatably mounted on the outer extremity of said arm structure, a kerf cutter pivotally mounted on said cutter head, said arm structure including arms adjustable horizontally about parallel vertical axes relative to the base to move the kerf cutter into different cutting positions relative to the base, and a motor on said base and relative to which said arm structure is adjustable for swinging said arm structure relative to said base, for rotating said cutter head and for swinging said kerf cutter relative to said cutter head.
44. In a mining apparatus, a portable base, a turntable mounted on said base for adjustment vertically relative thereto, an adjustable arm structure mounted on and overlying said turntable, a rotatable cutter head mounted on said turntable.

the outer extremity of said arm structure and carrying a kerf cutter, means for maintaining automatically the cutter head axis parallel to a common straight line during adjustment of 5 said arm structure relative to said turntable, and a motor on said turntable for swinging said arm structure and for rotating said cutter head relative to said arm structure.

45. In a mining apparatus, a portable base, 10 a turntable mounted on said base for adjustment in a vertical direction relative thereto, an adjustable supporting structure mounted on and overlying said turntable, a rotatable cutter head mounted on the outer extremity of said supporting 15 structure and carrying a kerf cutter, means for maintaining automatically the cutter head axis parallel to a common straight line during adjustment of said supporting structure horizontally relative to said turntable, and a motor on 20 said turntable for swinging said supporting structure and for rotating said cutter head relative to said supporting structure.

46. In a mining apparatus, a portable base, 25 kerf cutting mechanism on said base including a cutter head rotatable about an axis extending longitudinally of the base and a kerf cutter pivotally mounted on said cutter head for swinging movement relative thereto, means for adjusting said cutter head in a direction horizontally relative to said base while the head axis is automatically maintained longitudinally of the base and always parallel to a common straight line, and a motor on said base relative to which said 30 cutter head is horizontally adjustable for horizontally adjusting said cutter head and for rotating said cutter head about its axis.

47. In a mining apparatus, a portable base, a 40 horizontal turntable thereon, an arm structure pivotally mounted on said turntable to swing horizontally relative thereto to move its outer extremity from one side of said base to the other, a support pivotally mounted on the outer extremity of said arm structure to swing relative thereto about an axis parallel with the pivotal axis 45 of said arm structure, a cutter head rotatably mounted on said support about an axis extending longitudinally of the apparatus, a kerf cutter pivotally mounted on said cutter head to swing relative thereto, means for swinging said arm structure relative to said turntable, and means for swinging said support relative to said arm structure.

48. In a mining apparatus, a portable base, a 50 horizontal turntable thereon, an arm structure

5 pivotally mounted on said turntable to swing horizontally relative thereto to move its outer extremity from one side of said base to the other, a support pivotally mounted on the outer extremity of said arm structure to swing relative thereto about an axis parallel with the pivotal axis of said arm structure, a cutter head rotatably mounted on said support about an axis extending longitudinally of the apparatus, a kerf cutter pivotally mounted on said cutter head to 10 swing relative thereto, means for swinging said arm structure relative to said turntable, and means for simultaneously swinging said support relative to said arm structure for maintaining the head axis always parallel to a line extending 15 longitudinally of the apparatus.

49. In a mining apparatus, a portable base, a horizontal turntable thereon, a horizontal arm structure pivotally mounted on said turntable to swing horizontally relative thereto, said arm 20 structure overlying said turntable and at its forward extremity overhanging said turntable and base, a cutter support pivotally mounted on the outer overhanging extremity of said arm structure to swing relative thereto about an axis parallel 25 with the turntable axis, a kerf cutter pivotally mounted on said cutter support to swing relative thereto, means for swinging said arm structure, and means for swinging said cutter support relative to said arm structure.

50. In a mining apparatus, a portable base, a horizontal turntable thereon, an arm structure mounted on said turntable to swing horizontally relative thereto to move the outer end of said arm structure from one side of said base to the 35 other, said arm structure making like angles with the median longitudinal line of the apparatus at the opposite extremes of such swinging movement, a cutter support pivotally mounted on the outer end of said arm structure to swing relative thereto about an axis parallel with the pivotal axis of said arm structure, a kerf cutter pivotally mounted on said cutter support to swing 40 relative thereto about a horizontal axis in vertical planes extending longitudinally of the apparatus, and means for swinging said cutter support relative to said arm structure during swinging of the latter horizontally relative to the turntable thereby to always maintain the kerf cutter 45 parallel to aforesaid longitudinally extending vertical planes during swinging of said arm structure relative to said turntable.

CHARLES F. OSGOOD.
